UNITED STATES PATENT OFFICE.

ADDIS E. CHAMBERLAIN, OF CINCINNATI, OHIO.

COOK STOVE AND RANGE.

SPECIFICATION forming part of Letters Patent No. 269,829, dated January 2, 1883.

Application filed July 25, 1882. (No model.)

To all whom it may concern:

Be it known that I, ADDIS E. CHAMBERLAIN, of the city of Cincinnati, in the county of Hamilton and State of Ohio, have invented certain new and useful Improvements in Cook Stoves and Ranges, of which the following is a specification.

My invention relates to cook stoves and ranges.

10 The main object of my invention is to utilize the heat which, along with the smoke, passes from the combustion-chamber, and which in ordinary cases is lost.

15 The principal features of my invention consist in a novel arrangement of the flues of the stove.

20 In the accompanying drawings, making part of this specification, Figure 1 represents a perspective view of a cooking-range embodying my invention, the side of the stove next the observer and certain other portions, as shown, being broken away to admit of an inspection of the interior of the stove. Fig. 2 represents a vertical transverse section of the stove, taken at 25 the dotted line $x-x$ of Figs. 1 and 4, the tower being omitted. Fig. 3 represents a vertical transverse section of the stove, taken at the dotted line $y-y$ of Figs. 1 and 4. Fig. 4 shows a vertical section of the stove, taken through 30 its longitudinal center, those portions of the stove shown in Fig. 1 which are above the top plate and out of the plane of this section being omitted from this drawing; and Fig. 5 is a perspective view of a part of said stove, 35 showing the mode in which a hot-air flue may be changed into a working-flue, portions of the stove being broken away to exhibit said additional flue and its connections; Fig. 6, Sheet 3, is a top view of the stove, the top being removed; and Fig. 7 is a top view of the bottom of the stove, the rest of the stove having been removed.

40 A indicates the stove; B, the base or bottom plate; C C, the sides; D, the front end; E, the rear end, and F the top.

45 A fire-chamber, G, of any suitable construction, is at the front end of the stove, and is contiguous to the forward oven, H, having front end, H' , bottom H^2 , rear end, H^3 , top H^4 , and partition H^5 between said oven and said fire-chamber. The rear oven, I, has a top, I' , a front, I^2 , a bottom, I^3 , and a rear end, I^4 .

Flue a is thereby formed over the top of oven H. The space between the rear wall of oven H and the front wall of oven I and the space 55 between the bottom H^2 of the oven H and the base-plate B is divided longitudinally by the vertical partition J, thereby forming the side diving-flues, b b , and central flue, K' , the bottom flues, d d , and the central return bottom flue, e . Between the bottom I^3 of oven I and base B is flue f . Flue e aforesaid at rear opens into flue f . Below flue e and for a distance in flue f the base B has a depression, B' , thus enlarging the capacity of this flue e and 60 enabling it to readily receive and allow of a ready passage through it of all the heated air and smoke coming through the flues d d . (See more particularly Figs. 4, 5, and 7.) Flue f connects with flue g , formed between the back 70 wall, I^4 , of oven I and the rear end of the stove. This latter flue may enter directly into the smoke-discharge pipe. The straight discharge-flue h is formed between the top of the stove and the top of oven I, and may open directly 75 into the smoke-discharge pipe. The top of flue K' , (see Fig. 4,) formed between the vertical portions of partitions J and between the rear wall of oven H and front wall of oven I, is in the present instance closed at the top 80 by a suitable plate, as K, and open at bottom into flue e , and forms a hot-air chamber. It may, however, be arranged, as shown in Fig. 5, to form a part of the working-flues, and of such arrangement mention will herein be sub- 85 sequently made.

A sliding damper, L, extends transversely across the stove at or about the point shown in flue h .

The mode in which the devices already described operate is as follows: When the damper L is open the heated air and smoke pass through flue a and flue h , through the damper, into the discharge-pipe, thereby heating the top of ovens H and I. The front of oven H 90 is heated by the fire-chamber G. Oven H is thus heated in a common manner, and oven I partially heated, sufficiently to be used as a warming-chamber.

In operating the features of my invention 100 already described the damper L is closed, and the heated air and smoke pass through flue a , down diving-flues b , thence through flues d , then through return-flue e , thence through flue

f, under oven I, to flue *g*, through which latter it passes into the discharge-pipe or other intermediate passage-way arranged to receive it. The air in the perpendicular flue or chamber *K'* is heated, and thus the ovens II and I are heated on every side, and bread can be baked simultaneously in both ovens.

Another feature of my invention consists as follows: The residue of heat remaining in the hot air and smoke after passing through the flues, as described, may be still further utilized by causing it to heat a boiler, as *M*, the presence of the diaphragm *N* and the preferred location of the discharge-pipe at the end *M'* of the reservoir, as shown in Figs. 2 and 3, compelling the smoke, &c., coming by way of flue *g* to come into contact in flue *k* with the entire bottom surface of the boiler, and the diaphragm *P* compels the smoke, &c., coming through flue *h* when the damper is open to likewise travel beneath the entire bottom of the boiler. When desired, instead of the boiler *M*, a center and lids may be substituted, being preferably located at the dotted line *z z* of Fig. 4, and the usual stove utensils for cooking, &c., be heated there.

A third feature of my invention for still further abstracting the heat from the smoke, &c., is the tower *T*, consisting of two tiers of chambers or ovens, *R* and *S*, provided with suitable doors, as *R'* and *S'*, the hot air and smoke from the stove being compelled to pass through the pipe or flue *m* into the flue *n*, interposed between the upper and lower ovens, and thence into the flue *p*, and thence into the discharge-pipe *t*, thereby warming the chambers sufficiently for light baking. To utilize the hot-air flue or chamber *K'* as a working-flue, I form a horizontal flue, *W*, above oven I, as shown in Fig. 5. I connect this flue at its rear end to the rear flue, as *h*, or the discharge-pipe, and the forward end of the said flue to the upper end of the flue *K*, and place at the junction of flues *K* and *W* a damper, *K'*, for controlling the flow of gases through the last-named flues. By closing damper *L* and opening damper *K'* the heated fluids will pass from the fire-chamber through flue *a*, flues *b* and *d*, through flue *e*, and up through flues *K* and *W* to the discharge-pipe. By closing damper *L* the fluids pass around the ovens in the course first described in this specification.

While the various features of my invention are preferably employed together, they may be used independently of each other, and one or more may be used, so far as applicable, in stoves of a construction different from that herein shown.

What I claim as new and of my invention, and desire to secure by Letters Patent, is—

1. In a cook stove or range having two ovens,

the narrow deep return-flue *e*, located under the forward oven, and the wide shallow flue *f*, extending under the whole or the most part of the bottom of the rear oven and receiving the contents of flue *e*, and in combination with diving and rising flues and dampers, substantially as and for the purposes specified.

2. In a cook stove or range having ovens *H* and *I*, and flues arranged substantially as described, the damper *L* and the diaphragms *P* and *N*, for compelling the fluids to traverse the entire length of flue *k*, all combined substantially as and for the purposes specified.

3. In a cook stove or range, the combination of the discharge-pipe of the stove and the tower *T*, consisting of the double tier of ovens, flue *m*, interposed flue *n*, and flue *p*, substantially as and for the purposes specified.

4. In a cook stove or range, the combination of the flues *a b d e f g h*, damper *L*, flue *K'*, damper *K'*, and flue *W*, substantially as and for the purposes specified.

5. In a cook stove or range, the ovens *H* and *I*, flues *a h*, damper *L*, diaphragm *P*, flues *b d e f g*, diaphragm *N*, and flue *k*, in combination, substantially as and for the purposes specified.

6. In a cooking stove or range having two ovens, the diving-flues *b*, located between said ovens, in combination with the smoke-chamber *K'* and flues *f* and *g*, substantially as and for the purposes specified.

7. In a cook stove or range, the combination of the discharge-flues *k m n* and discharge-pipe *t*, substantially as and for the purposes specified.

8. In a cook stove or range having two ovens, the combination of the narrow deep return-flue *e*, located under the forward oven, the wide shallow flue *f*, extending under the bottom of the rear oven and connected to flue *e*, the damper *L*, and the co-operating flues for enabling the stove to be operated by a single damper, substantially as and for the purposes specified.

9. In a cook stove or range, the combination of the rear discharge-flue, *k*, the flues *h* and *g*, and the diaphragms *P* and *N*, for compelling the fluids to travel the entire length of said flue *k* before escaping from the stove, substantially as and for the purposes specified.

10. In a cook-stove having two ovens, the bottom *B*, having the depression *B'*, forming with partitions *J* the deep flue *e* under the forward oven and extending into the broad flat flue *f* under the rear oven, substantially as and for the purposes specified.

ADDIS E. CHAMBERLAIN.
